[57] CLAIM

The ornamental design for an add-on vehicular storage compartment, as shown and described.

DESCRIPTION

FIG. 1 is a front perspective view of an add-on vehicular storage compartment showing my new design, the broken lines representing the fragmentary portion of a vehicle dashboard which is shown for illustrative purposes only;

FIG. 2 is a front elevation view thereof;

FIG. 3 is a back elevation view thereof;

FIG. 4 is a top plan view thereof;

FIG. 5 is a bottom plan view thereof; and

FIGS. 6 and 7 are opposite side elevation views thereof.
